UNITED STATES PATENT OFFICE.

DALRIDGE B. BEAVERS, OF WASHINGTON, DISTRICT OF COLUMBIA.

WIRE REEL.

Application filed September 21, 1921. Serial No. 502,213.

To all whom it may concern:

Be it known that I, DALRIDGE B. BEAVERS, a citizen of the United States, residing at Washington, in the District of Columbia, have invented new and useful Improvements in Wire Reels, of which the following is a specification.

One object of my said invention is the provision of a reel constructed with a view to facilitating the handling of wire, more particularly cross-connecting or "jumper" wires in telephone central office terminal rooms, the said reel being adapted for the mounting of a coil of wire and to be expeditiously and easily expanded in the coil and to be as readily contracted for the removal of a coil and for the mounting on the reel of a fresh coil.

Another object is the provision of a reel characterized by the capacity to adequately support the side portions of a coil of wire as well as the central portion of the coil, and this without the liability of one or more of the side coils overhanging the reel and interfering with the operation of the reel incident to the paying off of wire.

Another object is the provision of a reel embodying means for expeditiously and easily and at the same time positively expanding and contracting the reel.

To the attainment of the foregoing the invention consists in the improvement as hereinafter described and definitely claimed.

In the accompanying drawings, forming part of this specification:

Figure 1 is a front elevation illustrating a coil of wire positioned on my novel reel and also showing the reel in its contracted state.

Figure 2 is a plan view of the contracted reel per se.

Figure 3 is a front elevation showing the reel as expanded.

Figure 4 is an enlarged horizontal section illustrating the construction at the inner end of the reel.

Figure 5 is a detail enlarged diametrical section of the construction at the outer end of the reel.

Figure 6 is an enlarged transverse section taken on the line 6—6 of Figure 5.

Figure 7 is a fragmentary transverse sec-

tion on the line 7—7 of Figure 3 and illustrating the preferred manner of pivotally connecting the blades of the reel in couples.

Similar numerals of reference designate 55 corresponding parts in all of the views of the drawings.

Among other elements my improvement comprises a bracket 1 adapted to be associated with any appropriate support. As 60 best shown in Figure 4, the said bracket comprises plates 2 with spaced arms 3 in parallelism, the said arms 3 being connected by bolts 4 and nuts 5, and being maintained in spaced relation by interposed tubes 6 65 mounted on the bolts. In the said arms 3 of the bracket is secured preferably by nuts 7 a tubular bearing 8 which receives the shaft 9 of the reel. Inwardly beyond the inner arm 3 of the bracket the shaft 9 is 70 provided with an abutment 10 formed by preference of two nuts, one of the said nuts being adapted to serve in conventional manner as a jamb nut. Mounted on the inner portion of the shaft 9 and interposed between the abutment 10 and the adjacent nut 7 is a coiled spring 11, the function of which is to tension the shaft 9 and the reel as a whole with a view to preventing too free 75 rotation of the reel. The practical advantage of this provision will be appreciated when it is stated that in the absence of tensioning means such as described, the pulling of a portion of wire from the coil, designated by 12, would likely be attended by a 80 continued rotation of the reel and the coil with the result that an excess length of wire would be paid off the reel.

As clearly appears in Figures 1, 2, 3 and 5, the outer end portion of the shaft 9 is 90 threaded as designated by 13, and a cap 14 is mounted on the free end of the shaft to serve as a stop against outward movement of the wheel-like nut 15 which is threaded on the shaft portion 13 and is provided with a lateral handle 16. In the inner portion of the hub of the said nut 15 is a circumferential groove 17 in which is seated the inwardly directed flange 18 of a sectional collar 19, with the result that the said collar 19 is connected in swivel manner with the nut 15. The sections of the said collar 19 95

are connected by screws 20 or other appropriate means with the outer head 21 of the reel. The reel also comprises an inner head 22 which is fixed to the shaft 9 by a set 5 screw 23 or other appropriate means, it being understood in this connection that the head 22 is fixed to the shaft 9 while the outer head 21 is movable on the shaft rectilinearly toward and from the inner head 10 22. Each of the heads 21 and 22 is provided with a circumferential groove 24, and each head has seated in its circumferential groove 24 an annular device 25 for pivotally connecting to the heads the ends of 15 certain of the blades 26. The said blades 26 are straight, and are arranged in pairs, and the blades comprised in each pair are pivotally connected together in lapped relation at their centers preferably in the manner 20 shown in Figure 7. It will also be readily noted from the drawings that one end of one blade in each pair is pivotally connected to the head 21, and that one end of the other blade of said pair is pivotally connected to the head 22. From this it follows that inward rotation of the nut 15 will be attended by expansion of the reel, while outward rotation of the said nut 15 will be accompanied by contraction of the 30 reel. The straight character of the blades 26 and the arrangement of the blades relatively to each other and to the heads 21 and 22 are of material advantage, inasmuch as they assure the periphery of the reel being of a diamond shape or of an obtuse angle shape. In virtue of this it will be understood that when the reel is expanded in the opening within a coil of wire the blades 26 will exert outward pressure against the 35 side convolutions of the coil as well as against the central convolutions of the coil, and it will be noted also that the outward inclination of the free portions of the blades 26 will preclude the outer convolutions of 40 the coil overlapping the ends of the blades. From this it follows that incident to the use of the reel there is no liability of any portion of the coil of wire 12 interfering with the free operation of the reel. 45

50 In the practical use of my novel reel, the reel is maintained in horizontal position, and while the reel is in a contracted state, as shown in Figures 1 and 2, a coil of wire 12 is placed on the reel so that the blades 26 are in the opening within the coil. The nut 15 is then manually turned in clockwise direction, and hence the blades 26 will be flexed and moved outwardly to expand the reel within the coil 12, and this until the 55 blades 26 bear solidly against the coil. With this done, it will be apparent that the coil of wire 12 will be conveniently mounted in such manner that it may be rotated with but little effort simply by drawing upon the end portion of the wire, and then when the

length desired is let off of the reel it will be understood that because of the tensioning of the reel the cessation of pulling on the wire will be followed by an immediate stoppage of the rotation of the reel. 70

Notwithstanding the practical advantages ascribed to my novel reel, it will be readily appreciated that the same is simple and inexpensive in construction and is well adapted to withstand the usage to which devices of analogous character are ordinarily subjected. 75

The construction herein illustrated and described has been reduced to actual practice and has been successfully operated, and I therefore desire it understood that I prefer the said construction with all of the details hereinbefore specifically set forth. I do not desire, however, to be understood as confining myself to the specific construction 80 and relative arrangement of the parts comprised in the reel, inasmuch as in the future practice of my invention such changes or modifications may be made as fairly fall within the purview of my invention as defined in my appended claims. 85 90

Having thus described the invention, what I claim and desire to secure by Letters Patent, is:

1. A reel having heads, one of which is movable rectilinearly toward and away from the other, and straight blades arranged in pairs with the blades pivotally connected together at their centers and with one end of one blade connected to one head and the other end of the other blade connected to the other head, in combination with a shaft carrying the said heads and having an outer threaded portion, and a manually-movable nut mounted on the threaded portion of the shaft outwardly beyond the said movable head and coupled in swivel manner to said head; the inner portion of said shaft being journaled in an appropriate support, and tensioning means interposed between the said support and an abutment on the shaft inwardly from the support. 100 105 110

2. A reel construction comprising a bracket with spaced and parallel arms, bolts and nuts connecting said arms, tubes mounted on the bolts and interposed between the arms to maintain the same in spaced relation, a tubular bearing mounted in and extending between the arms, nuts threaded on said tubular bearing and disposed at opposite sides of the arms, a shaft journaled in the tubular bearing and extending inwardly beyond the same and provided on its inner portion with an abutment, a spring surrounding said shaft portion and interposed between the abutment on the shaft and the adjacent nut, an inner head fixed on the shaft, an outer rectilinearly movable head on the shaft, said heads having circumferential grooves, a manually movable nut 115 120 125 130

threaded on the shaft outwardly beyond the rectilinearly movable head, said nut having a circumferential groove, a collar connected to the movable head and having a flange disposed in said groove of the nut, and straight blades arranged in pairs with the blades of each pair pivotally connected together and

with the ends of the blades of each pair connected one to one head and the other to the other head.

In testimony whereof I affix my signature.

DALRIDGE B. BEAVERS.
